UNITED STATES PATENT OFFICE.

CHARLES HIGHERS, OF VICKSBURG, KENTUCKY, ASSIGNOR TO CHARLES WIGGINS, OF VICKSBURG, KENTUCKY.

WHIFFLETREE.

SPECIFICATION forming part of Letters Patent No. 718,457, dated January 13, 1903.

Application filed August 30, 1902. Serial No. 121,648. (No model.)

To all whom it may concern:

Be it known that I, CHARLES HIGHERS, a citizen of the United States, residing at Vicksburg, in the county of Livingston and State 5 of Kentucky, have invented a new and useful Whiffletree, of which the following is a specification.

This invention relates to draw-bars, and is particularly designed to provide an improved 10 whiffletree wherein the body of the device is materially strengthened and stiffened. It is furthermore designed to provide the ends of the whiffletree with improved means for connecting the traces thereto in a simple and 15 efficient manner, said means being adapted to prevent accidental displacement of the traces and at the same time to permit of removal of the traces whenever desired.

With these and other objects in view the 20 present invention consists in the combination and arrangement of parts, as will be herein-after more fully described, shown in the accompanying drawings, and particularly pointed out in the appended claims, it being understood 25 that changes in the form, proportion, size, and minor details may be made within the scope of the claims without departing from the spirit or sacrificing any of the advantages of the invention.

30 In the drawings, Figure 1 is a plan view of a whiffletree embodying the features of the present invention. Fig. 2 is an inverted plan view. Fig. 3 is a longitudinal sectional view thereof. Fig. 4 is an enlarged detail cross-section on the line 4-4 of Fig. 3. Fig. 5 is a 35 detail perspective view of the brace-bar with the terminal trace-hooks.

Like characters of reference designate corresponding parts in all of the figures of the 40 drawings.

Referring to the accompanying drawings, 1 designates the body of the whiffletree, which is of wood, is substantially cylindrical in 45 shape and tapers gradually in opposite directions from the middle thereof. In the back of the whiffletree there is provided a longitudinal groove or seat 2, which communicates at its opposite ends with transverse grooves, notches, or seats 3, formed across the 50 extremities of the whiffletree.

A metallic stiffening and strengthening rod

or bar 4 is fitted snugly in the groove 2 in the back of the whiffletree and is twisted at its middle into an eye 5 for connection with a vehicle. Each end of the rod or bar is bent 55 into a substantially U-shaped hook 6, which is disposed transversely across the end of the whiffletree and is also projected in front thereof, the shank 7 of which is fitted snugly in the notch or seat 3 of the adjacent end of the 60 whiffletree, the outer extremity of the bar being bent transversely inward across the shank and in alignment with the whiffletree, so as to form a spring-tongue 8, which normally closes the entrance into the hook to prevent 65 accidental displacement of a trace-link. It will of course be understood that a trace-link can be snapped into engagement with the trace-hook by pressing the link against the spring-tongue 8, whereby the latter will be 70 displaced so as to permit the link entering the hook, after which the spring-tongue will snap back into its original position, and thereby close the hook against accidental displacement of the link.

75 Equally at opposite sides of the eye 5 are bands or rings 9, which snugly embrace the whiffletree and the rod or bar 2 and are held against displacement in an endwise direction upon the whiffletree by means of pins or similar fastenings 10, driven through the bands and into the whiffletree. Similar bands 11 are fitted to the ends of the whiffletree, so as to hold the ends of the rod or bar 2 in place and also prevent splitting of the tree.

80 85 From the foregoing description it is apparent that the device of the present invention is very strong and durable and at the same time is comparatively light, as it combines wooden and metallic parts in such a manner as to give strength and durability and at the same time to retain the lightness of an ordinary whiffletree.

85 What I claim is—

1. A whiffletree having its rear side provided with a longitudinal groove, a rod or bar fitted in said groove with an intermediate portion formed into an eye, and its terminals formed into substantially U-shaped trace-hooks extending across and fitted 100 against the ends of the whiffletree, with the extremities of the bar bent transversely in-

ward across the shanks of the respective hooks and in alinement with the whiffletree to form spring-tongues for closing the entrance into the hooks, bands or rings embracing the whiffletree and the rod or bar at a plurality of points, and means for holding the bands against displacement.

2. A whiffletree comprising a wooden body provided at its back with a longitudinal groove and having transverse recesses at its ends communicating with the groove, a stiffening rod or bar fitted in the groove and provided between its ends with an eye and having its ends bent forwardly and arranged in

the transverse recesses and provided with trace-engaging devices, and bands or rings embracing the body portion of the whiffletree and retaining the stiffening rod or bar in the longitudinal groove, substantially as described.

In testimony that I claim the foregoing as my own I have hereto affixed my signature in the presence of two witnesses.

CHARLES HIGHERS.

Witnesses:

JOE WIGGINS,
CHARLIE WIGGINS.
